UNITED STATES PATENT OFFICE.

PHILO M. BEERS, OF BRIDGEPORT, CONNECTICUT.

MECHANISM FOR GROOVING SEWING-MACHINE-NEEDLE BLANKS.

SPECIFICATION forming part of Letters Patent No. 258,695, dated May 30, 1882.

Application filed December 2, 1881. (No model.)

To all whom it may concern:

Be it known that I, PHILO M. BEERS, of Bridgeport, county of Fairfield, State of Connecticut, have invented an Improvement in 5 Mechanism for Grooving Sewing-Machine-Needle Blanks, of which the following description, in connection with the accompanying drawings, is a specification.

This invention relates to mechanism for 10 grooving sewing-machine-needle blanks, and is adapted for use in connection with mechanism substantially such as represented in my Patent of the United States No. 217,921, July 29, 1879. That patent shows a machine 15 provided with cutters to groove a sewing-machine-needle blank, the said blank being placed in and removed from the holding-jaws by a hand operation, the machine therein represented requiring the service of an attendant.

20 The object of this present invention is to arrange several grooving-machines—substantially such as represented in the said patent or of other suitable or well-known kind—in a mechanical organization in connection with needle-blank feeding and removing mechanism, whereby the said grooving-machine may be brought intermittently into position before mechanism which will supply a needle-blank to the needle-blank-holding jaws. In order 25 that the said grooving-machine may operate upon the said blank in the usual way, I have provided a movable support for the grooving-machines, it bringing each machine into position to be automatically supplied with a blank, 30 and subsequently into position to have the grooved blank or needle taken from it, one machine taking a plain blank while another machine on the support gives up its grooved blank.

35 As herein provided, I have shown a contrivance for containing six machines, which have needle-blanks automatically supplied to and taken from them, the attendant only being required to keep the blank-receiving hopper properly filled with needle-blanks.

40 Figure 1 of the drawings represents in partial vertical section a sufficient portion of my improved mechanical organization and one needle-grooving machine mounted thereon to 45 illustrate my present invention, the said figure showing at the left the blank-receiving hopper and mechanism to supply the groov-

ing-machine with a blank. Fig. 2 is an enlarged detail of the upper part of one of the grooving-machines, looking at it from the side. 55 Fig. 3 is a detail showing the mechanism for withdrawing a grooved blank from the blank-holding jaws of the machine. Fig. 4 is a top view of my improved mechanism, the rotating grooving-machine carrying-bed being shown 60 as provided with six rectilinear figures, each of which is supposed to represent a grooving-machine such as represented in Fig. 1 and substantially such as described in my patent referred to. Fig. 5 is a partial horizontal section of Fig. 1 on the dotted line x x , to illustrate the mechanism employed by me in this instance to rotate the grooving-machine support intermittently. Fig. 6 is a detail representing the needle-blank-holding jaws, the 65 means employed to automatically open and close them, and part of the mechanism which supplies the grooving-machine with blanks, the said figure clearly illustrating parts which, because of lack of space on the drawings, cannot be shown clearly in Fig. 1; Fig. 7, details of the cam and arm forming part of the locking device for the needle-blank-holding clamp; Fig. 8, an enlarged detail of the front of the carriage which holds the blank-clamping jaws 70 and part of the bed F and device to move the said carriage backward. Fig. 9 is an enlarged side elevation, showing more fully the needle-blank-feeding mechanism and the hopper detached from the machine. Fig. 10 is a top 75 view of Fig. 9; Fig. 11, a front end elevation of Fig. 9, looking at it from the left; and Fig. 12, a partial top view to show the two movable slides which receive between them the needle-blank which is next to be acted upon by 80 the ejector, the said slides being first moved from their position Fig. 11 to place the blank held between them in line with the ejector. These figures, 9 to 12, inclusive, show fully parts which, because of the size of the other figures 85 of the drawings, could not be well shown. Fig. 13 is a detail showing the hub, its pin, and the star-wheel moved by it and the lever moved by the grooved part of the hub.

90 Referring to the drawings, A is supposed to represent a machine for grooving needles—a machine substantially such as represented in my United States Patent referred to.

B represents a movable or rotating support,

upon which are mounted two or more grooving-machines, A, there being in this present instance six such grooving-machines, supposed to be shown in the drawings by the letters A in Fig. 4. This movable support B has connected with it a star-wheel, E, having curved faces A² and slots a², the latter receiving a downwardly-extended pin, b, (see Figs. 13 and 5,) of an arm, b², of a hub, b³, secured to an upright shaft, b⁴, which is rotated continuously through bevel-gears b⁵ b⁶ and driven shaft b⁷ in any well-known way. The continuous rotation of the hub b³ causes its pin b to enter and leave in succession each slot a² of the star-wheel E and operate the said star-wheel and its connected support B intermittently, the movement of the star-wheel being sufficient to actuate the movable support B far enough to carry each grooving-machine a distance equal to the distance between the blank feeding and removing mechanism, or one-sixth of a revolution. So long as the pin b is in one of the slots a² of the wheel E the latter will be moved by the said pin; but as soon as the pin b leaves one of the said slots the cylindrical part or body of the hub b³, then in one of the concaved spaces A² of the wheel E, prevents it and the support B from being rotated until the pin b, during the rotation of the hub and its arm b², is again brought into a slot, a². This intermitting pin and star-wheel motion is very common in the arts, and is not of my invention. Each machine, after it receives a blank, the support moving in the direction of the arrow, Fig. 4, holds the blank for nearly one entire revolution of the support B and grooves it as the said machine is carried by the support around into position opposite the mechanism for removing the blank.

Instead of the particular devices herein shown to operate the movable support B intermittently, I may employ any other well-known equivalent devices.

The shaft C, driven by suitable bevel-gear from shaft b⁷, as shown in Fig. 1, and extended up through a vertical bearing or sleeve, C⁴, which serves as an axis for the support B, has a gear, C², which engages a pinion, c, on the upright shaft c² of the grooving-machine. This gear C² in practice will be the common driver for the gears c of all the grooving-machines A carried by the support B. The shaft c² at its upper end has a grooved belt-pulley, c³, which is connected by belt c⁴ with the grooved belt-pulley a, which is the same as the pulley designated by like letter in the patent referred to.

The compound shaft s t and the gear r are the same as the like designated parts in the said patent; but instead of the toothed wheel h represented in the said patent I employ a bevel-faced wheel, (herein marked h,) which is engaged and driven by the bevel-wheel h² at the lower end of the shaft c², the said shaft having thereon a suitable movable hub or clutch, h³, by which, when desired, the mechanism for moving the grooving-cutters may be thrown out of or into operation by hand.

The gear c, loose on the shaft c², has at its upper side a pin, c⁵, which at suitable times is engaged by a corresponding pin, c⁶, on the hub of the clutch h³, splined upon the said shaft c² and grooved externally, to be embraced by a pin in the forked end of the shipper-lever m. This shipper-lever, pivoted at m² upon a rigid part, m³, of the frame-work, has at its other end a pin or knob, m⁴, by which to operate it to engage with or disengage the pin of the clutch from the pin of the gear c.

These grooving-machines A will each have the usual blank-holding jaws (herein marked d d²) to hold the needle-blanks while being grooved. The upper jaw, d, of suitable shape, is pivoted upon its carrying-lever d³, in order that it may adapt itself to the blank. This lever d³ has at its rear end a screw, d⁴, which is operated upon at the proper time by a cam, d⁵, on a shaft, d⁶. The front end of the shaft d⁶ has upon it a semicircular or other suitable arm, d⁷, which is intermittently operated upon at the proper time and partially rotated, to thus cause the cam d⁵ to close the jaw d upon jaw d² when the needle-blank is between them, the shaft d⁶ and its cam d⁵ constituting a locking device for the said jaws.

The stationary bed F has upon it a hopper, h⁵, to receive the needle-blanks to be grooved, also mechanism to grasp and remove a grooved blank; and near the said hopper and the said needle-blank-removing mechanism, respectively, are fingers e e². (See Fig. 4.) Just after the jaws near the hopper have been supplied with a needle-blank to be grooved the finger e acts upon the upper end of the arm d⁷ as the support B is moved in the direction of the arrow, Fig. 4, and turns the said arm, shaft, and cam so as to cause the jaw d to descend and grasp a needle-blank. The said cam d⁵ and its shaft remain in such position and lock the jaws together on the blank until the said machine, in the rotation of the support B, arrives opposite the blank-removing devices, (shown separately in Fig. 3,) when a second finger, e², also connected with the said bed F, strikes the under portion of the arm d⁷ and turns the shaft d⁶ and cam d⁵ in the opposite direction far enough to release the clamp d from the needle-blank, at which time the needle-blank-removing devices, comprising in part the pair of jaws G, are operated so as to cause the said jaws G to close upon or grasp the needle-blank and withdraw it from the needle-blank-holding jaws of the grooving-machine.

The jaws G have their fulcra g on an upright standard, g², bolted to a slide, g³, fitted in guideways g⁴. (See Fig. 4.) This slide g³ is provided with a slot, 40, through which is extended a pin, g⁵, carried by a long lever, g⁶. This lever g⁶ is shown in dotted lines, Fig. 4. The upper end of pin g⁵ is connected positively with the jaw-operating slide g⁷, fitted to be reciprocated for a short distance independently in the slide g³. In this way the first part of the movement of the lever g⁶ causes the jaw-

operating slide g^7 to be moved sufficiently far to cause the links g^8 , connected with the arms of the jaws G, to open or close the front ends of the said jaws, to thus release or grasp the blank before the pin g^6 strikes the parts g^9 or g^{10} of the slide g^3 , when thereafter, during the further movement of the lever g^6 , the slide g^3 and the jaw-operating slide g^7 move together with the jaws G closed. As the jaws G are moved backward, or in the direction of the arrow, Fig. 3, they will be closed and remain closed; but as soon as the lever g^6 is moved in a direction to push the slide g^7 forward the jaws will be opened, and as soon as the pin g^6 strikes the part g^{10} of the slide g^3 the said jaws will thereafter continue to move forward together, the jaws remaining open in position to be closed upon the projecting end of a grooved needle-blank, which is to be withdrawn from the grooving-machine at the next backward movement of the jaws. Each grooved blank withdrawn from the grooving-machine by the jaws will be released as the jaws are thereafter opened, permitting the grooved blank to drop into a suitable small pan, which in practice will be placed under the jaw G.

The lever g^6 has an arm, i , (shown in Figs. 5 and 13,) provided with a pin, i^2 , which enters a groove, 3 , in a cam or adjustable disk attached to the upper side of the hub b^3 , the said groove imparting to the said lever its movements at the proper times. The lever g^6 (shown in dotted lines in Fig. 4) has its opposite end suitably connected (see Figs. 6 and 11) with the slide h' fitted in suitable guideways, k^2 , connected with the bed F. This slide h' has upon it a bracket, k^3 , having connected with it an ejector, h^4 , which at the proper time is projected through the lower portion of the blank-holding hopper h^5 , the said ejector striking the end of the lower-most blank in the said hopper and pushing it out laterally into and between the open jaws d d^2 just before the jaw d is closed by the action of the finger e (before referred to) on the arm d^6 , which moves the shaft d^5 and cam d^4 .

Referring to the larger figures, 9 to 11, showing this blank-feeding mechanism fully and clearly on a larger scale, it will be seen that the slide h' is also provided with a cam-plate, h^6 , on which is an irregular cam-rib, h^7 , shaped as fully shown in Figs. 9 and 10, and a plate, h^8 , having near its forward edge a cam-depression, 4. (Shown clearly in Fig. 10.)

The rising block 5, which in practice forms a permanent part of the guideway-block k^2 , receives a screw-bolt, 6, which serves as the fulcrum for the hub (shown broken out in Fig. 9) of the slide-moving lever 7, having at its rear end a roller, 8, which is acted upon to vibrate the said lever by the cam-plate h^6 , the said roller being pressed against the said plate h^6 by the spring 9. The forward end of the lever 7 is slotted at its under side to loosely engage a pin, 10, on the slide-plate 12, fitted in guideways between the ledges 13 14 of the stationary part 5. The lever 7 moves the slide-plate 12 and its connected slide-plate 16, to be de-

scribed, in the direction of the arrow on it, Fig. 12; but in doing so the lever 7 transmits its effective pressure on the spring r^2 , held by studs r^3 of plate 12, so that the moving force is yielding rather than positive, which obviates breakage of parts if a blank gets clogged.

Referring to Fig. 12, where the hopper is removed, as well as the parts at the left of said ledge 14, it will be seen that the slide 12 is connected with an arm, 15, of a slide, 16, by means of a pin, 17, on slide 12, which enters a slot, 18, in the said arm 15, as shown in dotted lines.

In Fig. 12 part of the slide 16 is broken away at the right to show the arm 15 under it. The slide 16 is cut away centrally at 19 to surround a base-piece, 20, which receives a screw, 21, by which to attach the base 22 of the hopper h^5 to the part 5. The opening 19 is larger than the base-piece 20, so that the slide 16 may be moved longitudinally for a short distance. The slide 16 has a lug or ear, 23, in which is an adjustable screw, 24. The end of the screw 24 bears against the edge of the foot or base 22 of the hopper when the roller 8 of the lever 7 rests at the lowest point, 4, (see Fig. 10,) of the cam-plate h^6 , and by its position in the said ear governs the position of the front end of slide-plate 16 with relation to the vertical guideway or groove at the lower end of the hopper, down which the needle-blanks 60 descend, and out from which they are pushed by the spring presser-foot 27, to be hereinafter described, into the narrow groove 28 between the ends of the slide-plates 12 16. The plate 16 is provided with a pin, 25, (shown in dotted lines, Fig. 12, and in full lines, Fig. 11, by breaking out the part 5,) which enters a slot, 26, in the bed 5 and bears against a spiral spring, 30, laid in the said slot. One end of this spring rests against the bar 31, secured to the bed 5 by screws 32, and the said spring exerts its force in keeping the slide-plate 16 constantly pressed forward as far as the screw 24 will permit.

The left-hand inner wall of the vertical passage or way at the lower end of the hopper, viewing the hopper as in Fig. 11, will be taken as the point with which the end of the slide-plate 13 will be aligned when the two slide-plates are in their farthest position to the right. In such position and with such adjustment the pin 17 rests in the end of slot 18 nearest the plate 16 by reason of the pressure of spring 30, the movement of plate 12 being at that time arrested with its end in line with the right-hand inner wall of the bottom groove or discharge-opening of the said hopper.

The front part of the ejector h^4 is shown in Figs. 9 and 10 as held in a guide-block, 33, fast to the bed 5, and the forward end of the ejector is just in line with the passages 34 35 through the ledges 13 14. (See Fig. 12.)

The groove 28, formed between the ends of the slide-plates, when it receives a needle-blank, is directly under the hopper passage or outlet, and occupies substantially the position

with relation to passages 34 35 as in Fig. 12; but when the lowermost blank of the series has been pressed into said groove 28 the lever 7, by its pressure on the spring r^2 , moves the 5 said slide-plate 12, which, pressing against one side of the blank, carries it along horizontally until the blank and groove 28 come in line with the ejector h^4 , at which time the said ejector is moved forward, as described, by the lever g^6 10 and slide h' , forcing the needle-blank out from the groove 28, between the slide-plates 12 and 16, through the passage 35, between the needle-blank-holding jaws referred to. As the slides 12 and 16 are moved to carry the needle-blank from below the hopper to a position 15 in line with the ejector the end of slide-plate 16 bears on the blank with a yielding pressure, due to the force of spring 30.

The blanks for sewing-machine needles, they 20 having shanks of larger diameter than their blades, are liable to tip and lie very irregularly. I desire to keep three or four of the blanks at the lower end of the hopper in horizontal position, so that they may be readily 25 fed down into groove 28.

The passage-way at the lower end of the hopper h^5 is just wide enough for one needle-blank and deep enough to permit several needle-blanks to lie one on the other in a pile. At 30 one side of the hopper h , nearest the shanks of the blanks, I have cut a slot, 36, into which projects the free end of the blank-presser or presser-foot 27, carried at the end of the lever 38, having its fulcrum 39 in the head of a 35 swiveling block, 40, mounted in an ear, 41, rising from the bed 5. This lever, at its rear end, has a grooved shoe, 43, which rides on the cam-rib h^7 of the plate h^6 .

The lever 38 is acted upon by a spring, 42, 40 which keeps the shoe 43 always on the rib h^7 .

This cam-rib is so shaped and moves the lever 38 in such time and order with relation to the slides 12 and 16 and the ejector that the presser 27 will be withdrawn from the slot 36 45 when the slide h' and ejector h^4 have been moved fully forward, and the end of the presser 27 will at the same time be lifted with its end in position about level with the second needle-blank from the pile of blanks at the 50 bottom of the hopper. At this time the shoe 43 will rest on the lowest part, 44, of the cam-rib h^7 . As the slide h' is drawn backward to draw back the ejector h^4 the part 45 of the cam-rib, (see Fig. 10,) acting on the shoe 43, 55 will move the lever 38, so that the point of the presser 27 will enter the slot 36 and pass between the shanks of, say, the second and third needle-blanks of the pile of blanks lying one directly above the other, and the further backward movement of the slide and cam-rib will bring the part 46 of the cam-rib under the said shoe and throw down the front end of lever 38, causing the presser to bear or press upon the shanks of the blanks below it with 60 very considerable force, so that as soon as the roller 8 of lever 7 reaches the low part, 4, of

the cam-plate h^8 and the slide-plates 12 and 16 are acted upon and moved by the spring 30 to place the groove 28 between their ends just below the open bottom of the hopper, the presser 27, then bearing on the needle-blanks, with the shoe 43 on the highest part 48 of the cam-rib h^7 , will cause the lowermost blank of the pile of blanks below the presser to be thrown down forcibly into groove 28. After this the 75 plates 12 and 16 will be moved laterally, as described, to place the needle-blank then in the groove 28 opposite the ejector.

The hopper h^5 is divided vertically through one of its walls by the groove 48, so that the 80 needle-blanks may be seen and touched, if necessary, and that half of the hopper at the right (see Fig. 10) which receives the shanks of the blanks is made larger or wider.

The jaws which hold the needle-blank to be 85 grooved will in this apparatus, as in my patented machine, be supported by a carriage, k , (designated by like letter in my patent referred to,) which carriage will be moved longitudinally by a suitable feed-screw and half-nut, as there- 90 in described, (and also just as described in United States Patent No. 184,347, to which reference may be had,) to thus carry the blank past and so that it may be subjected to the action of the regular grooving or milling cutters 95 of the usual grooving-machine, A.

In my patented machine, the needle-blank having been placed between the needle-blank-holding jaws, the carriage was moved back for a short distance by hand to enable the said carriage to turn a clutch-moving arm and engage the clutch on the so-called "compound" shaft $s t$, which clutch, as therein described, sets the machine in operation to automatically groove both sides of the needle-blank. In this 105 my present invention the jaws $d d^2$ are sup- 100 posed to be mounted upon just such a car- riage, k , as is shown and referred to in my said patent; but herein I have arranged to move the said carriage k backward automatically, 110 instead of by hand, for the distance necessary to set the machine in full grooving operation. This I have done by providing the front end of each carriage (see Fig. 8) with a roller, n , 115 having its journal in a bracket, n^2 , made adjustable by the adjusting-screw n^3 to adapt the said roller to the position of the jaws $d d^2$ on the carriage k . Just after the blank to be grooved has been clamped between the jaws $d d^2$ the roller n , as the support B is moved 120 forward, strikes the adjustable carriage-throwing-in device p and automatically throws back the carriage k , for the purposes stated in the 125 said patent.

The throwing-in device p is shown as a lever, 125 pivoted at p^2 on a block, p^3 , secured to the bed F, the said lever being made adjustable by the screw p^4 .

I have herein described the grooving-ma- 130 chine A as mounted on a movable support; but I desire it to be understood that my in- 135 vention would not be altered if the support B

was held fast and the bed F was made movable, instead of fixed, as has been so far described of it.

I have not herein described fully the operation of the grooving-machine A, as that will be understood by referring to my patent hereinbefore cited; nor have I deemed it necessary to show in detail more than one grooving-machine mounted upon the movable support B, I deeming it necessary only to show the positions upon the said table which the series of the said machines will occupy.

With an organization of mechanism such as herein described the grooving of needle-blanks is rendered substantially automatic and the service of an attendant for each machine is dispensed with, the hopper and the mechanism connected with it and the needle-blank-withdrawing mechanism, supported on the bed F externally to the movable support B, doing the work usually performed by the operators heretofore in attendance upon each grooving-machine.

I am aware that a rotating table has been provided with dies to hold a needle-blank and present one end of it successively to the operation of a series of tools to form an eye in the needle; and I am also aware that a traveling carriage holding a blank for a knitting-machine needle has been presented successively to the action of a series of dies.

I do not herein broadly claim the slide-plates and ejector; but said slide-plates have not been used in connection with an adjusting device to insure the correct position of the same.

I claim—

1. A series of needle-grooving machines, A, and the movable support therefor, combined with the mechanism, substantially as described, to automatically and successively operate the needle-blank-holding jaws of the said machines to grip and hold the blanks to be grooved, substantially as described.

2. A series of needle-grooving machines, A, and intermittently-rotating support B therefor, bed F, and needle-blank-holding jaws, and cam to automatically close them, combined with the needle-withdrawing mechanism adapted to automatically engage and withdraw a grooved needle-blank from the needle-grooving machine opposite it, substantially as described.

3. A series of needle-grooving machines, A, and intermittently-rotating support B therefor, bed F, and needle-blank-holding jaws, and the means to automatically close and lock them, as described, combined with a hopper and ejector, and the means, substantially as described, to operate the ejector to automatically transfer a needle-blank from the hopper into position

between the jaws to be grasped and held thereby while being grooved, substantially as described.

4. The bed F and hopper and ejector to move a needle-blank into position between the needle-blank-holding jaws, and the needle-withdrawing mechanism to automatically seize and withdraw a grooved blank from the needle-blank-holding jaws, combined with a series of needle-grooving machines having needle-blank-holding jaws, and with the intermittently-rotating support by which the said machines are brought one after the other in the proper order before the hopper and the needle-withdrawing mechanism, substantially as set forth.

5. The hopper h⁵ to contain the needle-blanks, slide-plates to remove a blank from the hopper, and an ejector for forcing the blanks into the blank-holding jaws, the bed F, and the carriage-throwing-in mechanism connected therewith, combined with the carriage k, and the automatically-operated needle-blank-holding jaws mounted thereon, substantially as described.

6. The intermittently-revolving support B, bed F, and needle-blank-holding jaws, combined with cam d⁴, shaft d⁵, arm d⁶ thereon, and fingers to strike the said arm and actuate the shaft and cam, substantially as described.

7. The needle-withdrawing mechanism, composed of the jaws G, the links, the jaw-actuating slide g⁷, and slide g⁸, to operate substantially as described, and the bed F, combined with the intermittently-revolving support B, a series of needle-grooving machines, A, and needle-blank-holding jaws thereon, substantially as and for the purposes set forth.

8. The hopper and the loosely-connected slide-plates 12 16, combined with the adjusting device 24, to insure the correct position of the forward end of the slide 16 with relation to the discharge-passage at the bottom of the hopper, substantially as described.

9. The hopper, the slide-plates, and the lever 38 and its presser 27, to engage and bear upon the needle-blanks, combined with a cam-ledge 105 to give to the said lever and presser the proper movements to enable the presser to press the needle-blanks down in the hopper at the proper times and between the slide-plates, substantially as described.

In testimony whereof I have signed my name to this specification in the presence of two subscribing witnesses.

PHILO M. BEERS.
